[57] CLAIM

The ornamental design for a newspaper vending bin or similar article, as shown and described.

DESCRIPTION

FIG. 1 is a perspective view of a newspaper vending bin or similar article showing my new design;
FIG. 2 is a front elevational view thereof;
FIG. 3 is a rear elevational view thereof;
FIG. 4 is a top plan view thereof;
FIG. 5 is a left side elevational view thereof, the right side being a mirror image of the left side shown; and
FIG. 6 is a bottom plan view thereof.
The broken line representation of areas for advertising indicia in FIGS. 1 2 and 5 is for purposes of illustration only and forms no part of the claimed design.

FIG. 1

FIG. 2

FIG. 3FIG. 4FIG. 5

FIG. 6
